UNITED STATES PATENT OFFICE.

JOSEPH D. BELL, OF SAN FRANCISCO, CALIFORNIA.

WALL OR CLOSET BED.

1,189,342.

Specification of Letters Patent.

Patented July 4, 1916.

Application filed September 22, 1913, Serial No. 791,049. Renewed October 31, 1914. Serial No. 869,714.

To all whom it may concern:

Be it known that I, JOSEPH D. BELL, a citizen of the United States, residing at San Francisco, in the county of San Francisco and State of California, have invented new and useful Improvements in Wall or Closet Beds, of which the following is a specification.

The present invention relates to improvements in that class of beds which are swung upward in order to be out of the way when not in use.

My improved bed may be used in either a recess or a closet or attached to a door, panel, or other closure of a closet, or to an arm or frame extending from a closet, or, in its simplest mode of use, it may be directly secured to a floor, adjacent to a wall of a room.

The object of the invention is to provide a bed of this character which will be simple, and therefore economical, in construction; easily, rapidly and conveniently movable into the position of use or disuse; which will occupy very little floor space when not in use; which will be adjustable for any weight of bedding; which, when in the position of use, cannot without close inspection be seen to be other than an ordinary bed; which does not require the use of heavy balancing weights, greatly increasing the cost of transportation; and particularly one which can be transported with the parts assembled ready for use, all that is required being to secure it to a floor or other support, which can be done in a very short time by an inexperienced person.

In the accompanying drawing, Figure 1 is a front view of my improved bed in an upright position; Fig. 2 is a side view of the same; Fig. 3 is a view similar to Fig. 2, except that the bed is lowered to the position in which the counterbalance springs begin to operate; Fig. 4 is a side view of the bed fully lowered; Fig. 5 is an enlarged plan view of a balancing device; Fig. 6 is a vertical section of the same on the line 6-6 of Fig. 5; Fig. 7 is a sectional view showing a detail; Fig. 8 is a plan view of the same; Fig. 9 is a sectional view showing a modified form of casting.

Referring to the drawing, 1 indicates supporting means for the bed comprising two castings which are secured by screws 2 to the floor of a room, and from which rise apertured lugs 3, and standards 4 having flanges

5 extending toward each other. Said lugs 3 form end bearings for trunnions 6 of a head support carrying means 7, comprising lower and upper horizontal members 8, 9, upright side members 10, and rearward extensions 15, having at the bottom outwardly extending flanges or ribs 25 which can engage the inwardly extending flanges 5. The upright members 10 are formed at their upper ends 65 to provide bearings 11 for a horizontal shaft 12, the ends of which are received in sockets 13, clamped around the tubular side bars 14 of the bed frame, the ends of said side bars being received in socketed ends of castings 70 16, which have thereon studs 17, by which are attached head and foot angle-irons 18 extending transversely of the bed, to which angle-irons are connected at suitable intervals the springs 19 of the wire mattress. Secured to said socketed ends by nuts 20 and bolts 21, of which the heads are contained within the tubular side bars, and which pass through apertures in said ends, are apertured ends of brackets 22, the outer ends of 80 which are reduced in thickness, and on which are pivoted, as shown at 23, the forked upper ends of the head and foot legs 24, 25 of the bed. To the outer ends of the brackets 22 at the foot of the bed are secured 85 the end members of the foot piece 27, and in said ends at the head of the bed are formed sockets 28, to partly receive the outer ends of levers 29, pivoted, as shown at 31, to the side bars 14 of the bed, and to which outer 90 ends are rigidly secured the end members of the head piece 32, said sockets being provided to allow the lower ends of said end members to rest upon the outer ends of the brackets. To mediate points of the levers 29 95 are connected ends of links 33, the other ends of which are connected to the legs 24 at the head of the bed, so that, when said levers 29 are swung from the position shown in Fig. 2 to that shown in Fig. 4, by the 100 same movement said legs are swung from a horizontal to a vertical position in line with the end members of the head piece 32. Said head piece is retained in the horizontal position shown in Fig. 2 by a latch bar 34, pivoted to a side bar of the bed frame, and having a hooked outer end which engages 105 a pin 36 on an end member of the head piece.

For the purpose of balancing the weight 110 of the bed, there are provided springs 37, coiled around a tube 38 around the shaft 12,

and between the bearings 11, the adjacent ends of each spring being inserted in holes in a circular flange 39 formed integral with said tube 38, and located centrally between 5 the upright members 10 of the head support, from which flange extends an arm 41, the outer end of which is secured to the angle iron 18 at the head of the bed by means of a bolt 42 passing through said angle iron 10 and then through a slot 43 in said arm, a nut 44 being secured upon the outer end of the bolt. The other ends of the coiled springs are inserted in holes in plates having ratchet teeth 46 and which loosely surround 15 the shaft 12 between the inner surfaces of the bearings 11, and the ends of the tube 38. Pawls 47 can engage the teeth of the segmental rack and prevent any rearward movement which might be caused by the 20 tension of the coiled springs. These pawls 47 are loose pieces formed on their under sides with concavities 48 (see Fig. 6) which can rock on round bosses 49 formed integral with the upper cross member 9 of the head 25 support. Each pawl has a tail 51 which, by its greater weight than the nose of the pawl, keeps said nose in engagement with a tooth of the corresponding ratchet segment. The tension of either spring can be varied as de- 30 sired by turning it so as to cause the pawl to engage a different tooth.

In lowering the bed from the upright position the tension of the springs 37 is not increased until the flanges 25 impinge 35 against the flanges 5. Until that occurs the tension of the springs 37 merely causes the head support to swing outward with the bed about the trunnions 6 as axis. But when the head support can no longer swing out- 40 ward by reason of the abutment of the flanges 25 against the flanges 5, the bed is then swung outward upon the shaft 12, and by this movement the coiled springs 37 are contracted around the tube 38, and their 45 tension is increased. As the bed is lowered the legs at the foot of the bed remain vertical, and the bed rests on said legs and on the head support. The latch bar is removed from the head piece and the head piece is 50 then raised, thereby moving the legs at the head of the bed into a vertical direction in line with the end members of the head piece.

It will be seen from Fig. 4 that the lower ends of said legs do not, when extended to 55 this position, come in contact with the floor, and therefore do not ordinarily support the bed, but they are of utility in forming a safety device, for preventing the bed tilting upward from the foot about the shaft 12 on 60 account of excessive tension of the counter-balance spring, and thus assure timid occupants that the bed is absolutely safe when extended. It will be observed that unless the legs are in this position insuring safety, 65 the head piece prevents the bed being occu-

pied. In addition to the practical utility of these legs at the head of the bed, they are of value in imparting to the bed a harmonious or symmetrical appearance and preventing it from having an unusual or unstable appearance. 70

56 indicates sheet metal holders, bent to conform in general to the cross-sectional form of the angle-irons, and to closely surround the same to slide thereon, and having 75 portions 57 bent outward from the outer member of the angle iron and formed with apertures 58, so registering with one another, that the straight portions of fingers 59, which hold down the edges of the mattress, 80 can pass through said apertures. Heretofore it has been required to form holes in said angle irons to attach thereto the clamps for holding said fingers. In my invention this construction is no longer required. 85

In the modification shown in Fig. 9, the casting 1 has upright extensions 53, having screw holes 54, by which they may be attached to a door or panel, or the end of a movable arm or frame which can be moved 90 out of a closet, instead of being fixedly attached to a floor. In other respects, the construction and mode of use of the bed remain the same.

Several advantages possessed by my improved bed appear at once from the description thereof. In addition it may be stated that the bed is very simple and economical in construction, since it consists mainly of an ordinary stock bed already on the market, 100 the changes and additions to be made thereto being very simple, and the amount of hand labor expended upon each bed being very small. A further very important advantage is that the bed is very well adapted 105 for transportation and sale in places remote from the factory, for two reasons, first, that the use of the balancing springs avoids heavy balancing weights and the cost of transportation is thus greatly reduced, and, 110 second, because the bed can be packed and transported ready for setting up, and all that is then required is that the castings 1 be screwed down to the floor in the proper position. 115

I regard also as a very important feature of my invention the pivotal connection between the head support and the castings 1 which are secured to the floor, which is advantageous for several reasons. The springs 120 are less contracted than they would otherwise be since they contract while the bed is swinging to the horizontal position only from the position shown in Fig. 3 instead of from that shown in Fig. 2. Again, since 125 the head support 7 swings outward, it can be made longer and still support the bed at the same height, and in consequence the axis of rotation of the bed, in swinging from the position shown in Fig. 3 to the position 130

shown in Fig. 4, is nearer the center of gravity than before, and consequently the tension of the springs to counter-balance the weight of the bed, as also the force required 5 to lift the bed, can be reduced. It is an obvious advantage to have the head of the bed move outward when it is lowered, and especially when the bed is contained in a closet or recess.

10 I claim:—

1. The combination of means for supporting a swinging bed, located wholly between the side lines of the bed and provided with means for immovably securing it against rotation about a horizontal axis, carrying means likewise located wholly between the side lines of the bed, and pivoted to said supporting means to rock about a horizontal transverse axis, a bar carried 15 by the upper portion of said carrying means and extending transversely beneath the bed and between the head and foot thereof and on which the bed is supported, and a spring coiled around said bar and arranged to be 20 compressed by the lowering of the bed.

2. The combination of an upwardly extending support for a bed, journals arranged to be secured to the floor, said support having trunnions in said journals by 25 which the support can rock about a horizontal axis through the journals, said journals having flanges and the support having flanges arranged to engage the journal flanges and arrest the rocking movement of 30 the support, a bar horizontally pivoted in the upper portion of said support, a bed frame supported by said bar, and a spring coiled around said bar, of which one end is movable with the bed and the other end is 35 sustained by said support.

3. The combination of an upwardly extending support for an end of a bed, pivots, said support being movable about a horizontal axis through the pivots, flanges 40 rigidly connected with said pivots and the support having flanges arranged to engage the first named flanges and arrest the swinging movement of the support, a transverse bar horizontally pivoted in the upper 45 portion of said support, a bed frame supported by said bar, and a spring of which one end is movable with the bed and the other end is sustained by said support.

4. The combination of a support for an 50 end of a bed having bearings in its upper portion, a bar rotatable in said bearings, a bed frame of which said bar forms a part, a tube around the bar between said bearings, coiled springs around said tube, means on 55 the central portion of said tube for holding adjacent ends of said springs, their other ends being sustained by said support, and

an operative connection between said means and the bed frame, whereby they move in unison.

5. The combination of a support for an end of a bed having bearings in its upper portion, a bar rotatable in said bearings, a bed frame of which said bar forms a part, a tube around the bar between said bearings, plates between the ends of the tube and said bearings, and having ratchet teeth, pawls movably carried by said support and engaging said ratchet teeth, coiled springs around said tube, and means, on 65 the central portion of said tube, for holding the adjacent ends of said springs, the other ends being secured to said plates.

6. The combination of a support for an end of a bed having bearings in its upper portion, a bar rotatable in said bearings, a bed frame supported by said bar, a tube around the bar between said bearings, a collar on the central portion of said tube, coiled springs around said tube on opposite 70 sides of said collar, the adjacent ends of said springs being secured to said collar, and the other ends being sustained by said support, and a bar extending from the 75 collar to the bed frame.

7. In a bed of the character described, the combination of side bars forming a part of the frame of the bed, brackets at the head of the bed each secured at one end to a side bar, their other ends having sockets 80 on the upper sides, levers pivoted to said side bars the outer ends of which are received in said sockets, and a head piece, the 85 end members of which are secured to said outer ends.

8. In a bed of the character described, the combination of side bars forming a part of the frame of the bed, brackets at the head of the bed each secured at one end to a side bar, their other ends having sockets on 90 the upper sides, levers pivoted to said side bars the outer ends of which are received in said sockets, a head piece, the end members of which are secured to said outer ends, links having ends connected to said levers, 95 and legs at the head of the bed to which the other ends of said links are connected, the parts being of length such that when the outer ends of said levers rest in said 100 sockets, said legs are in alinement with said 105 end members.

In testimony whereof I have hereunto set my hand in the presence of two subscribing witnesses.

JOSEPH D. BELL.
